CLAIM

The ornamental design for a dual sighting scope mount system, as shown and described.

DESCRIPTION

FIG. 1 is a perspective front view of a dual sighting scope mount system;

FIG. 2 is a front elevation view of the dual sighting scope mount system;

FIG. 3 is a rear elevation view of the dual sighting scope mount system;

FIG. 4 is a left side elevation view of the dual sighting scope mount system;

FIG. 5 is a right side elevation view of the dual sighting scope mount system;

FIG. 6 is a top plan view of the dual sighting scope mount system; and,

FIG. 7 is a bottom plan view of the dual sighting scope mount system.

The rifle and scope shown in broken lines for illustrative purposes only and form no part of the claimed design.
